(74) Attorney, Agent, or Firm: Rothwell, Figg, Ernst & Manbeck

(73) Assignee: **Mallinckrodt Inc.**, St. Louis, MO (US)

(57) CLAIM

The ornamental for a combined storage and delivery container system for a breathable gas, as shown and described.

(**) **Term:** **14 Years**

DESCRIPTION

(21) Appl. No.: **29/113,054**

FIG. 1 is a front elevational view of the invention.

(22) Filed: **Oct. 29, 1999**

FIG. 2 is a side elevational view of the invention.

(51) LOC (7) Cl. **24-04**

FIG. 3 is an opposite side elevational view of the invention.

(52) U.S. Cl. **D24/164**

FIG. 4 is a rear elevational view of the invention.

(58) Field of Search D24/164; 128/204.18,
128/205.24, 205.25, 205.12

FIG. 5 is a perspective view of the invention; and,

(56) References Cited

FIG. 6 is a top elevational view of the invention.
